CLAIM

The ornamental design for a hand-held spectrometer, as shown and described.

DESCRIPTION

FIG. 1 is an isometric view of a hand-held spectrometer; FIG. 2 is another isometric view of a hand-held spectrometer; FIG. 3 is a top view of a hand-held spectrometer; FIG. 4 is a bottom view of a hand-held spectrometer; FIG. 5 is a side view of a hand-held spectrometer; FIG. 6 is another side view of a hand-held spectrometer; FIG. 7 is a front ("head") view of a hand-held spectrometer; and, FIG. 8 is a rear view of a hand-held spectrometer. The broken lines in FIGS. 1-8 are for illustrative purposes only and form no part of the claimed design.
